FIG. 1

FIG. 2

FIG. 3

FIGURE 1 is a rear isometric view of a wire receptacle for trash cans and the like, showing my new design.

FIGURE 2 is a front isometric view thereof, with the cover in an open position.

FIGURE 3 is a front isometric view with the central portion in a raised position to accommodate the removal of a trash can enclosed therein.

The broken line representation of the trash can is shown for illustrative purposes only.

I claim:

The ornamental design for a wire can holder or similar article, substantially as shown and described.
